UNITED STATES PATENT OFFICE

2,328,004

LUBRICATOR

Emmet M. Green, Los Angeles, Calif., assignor to
 Lincoln Engineering Company, St. Louis, Mo.,
 a corporation of Missouri

Application May 22, 1941, Serial No. 394,690

5 Claims. (Cl. 123—196)

The present invention relates to lubricating systems and more particularly to lubricators adapted to supply lubricant to the valves and cylinders of internal combustion engines.

The present application is a continuation-in-part of my earlier co-pending application Serial No. 256,146, filed February 13, 1939, Patent No. 2,267,728, issued Dec. 30, 1941.

An object of the present invention is to provide a simple, inexpensive and efficient device for supplying lubricant to the valves and cylinders of internal combustion engines. Another object of the present invention is to provide a device which will supply a predetermined amount of lubricant to the valves and cylinders of internal combustion engines only when the engine is "cold." Still another object of the present invention is to provide a device which may be readily adjusted to give either initial lubrication or continuous lubrication of the valves and cylinders of internal combustion engines.

For the purpose of illustrating the invention, there are shown in the accompanying drawings forms thereof which are at present preferred, since the same have been found in practice to give satisfactory and reliable results, although it is to be understood that the various instrumentalities of which the invention consists can be variously arranged and organized and that the invention is not limited to the precise arrangements and organizations of the instrumentalities as herein shown and described.

Figure 1 represents a vertical cross-sectional view on a somewhat reduced scale, of one embodiment of the present invention as it appears immediately after the start of a "cold" motor.

Figure 2 represents a vertical cross-sectional view of the embodiment shown in Figure 1 as it appears after the measured charge of lubricant has been delivered to the intake manifold and after the feeding chamber has been replenished.

Figure 3 represents a vertical cross-sectional view of the embodiment shown in Figures 1 and 2 as it appears shortly after the motor has stopped and during the transfer of lubricant from the feeding chamber to the supply chamber.

Figure 4 represents a vertical cross-sectional view similar to Figures 1, 2 and 3 as the embodiment appears when the motor is in operation and when the flow regulator valve is in its closed position to give a continuous flow of lubricant from the reservoir through the feeding chamber to the supply chamber and thence to the intake manifold.

Figure 5 represents a fragmentary more or less

schematic view of an automobile equipped with the embodiment of the present invention shown in Figures 1 to 4 inclusive showing one possible position thereof and showing a sight-feed therefor provided at the instrument panel of the automobile.

Figure 6 represents a more or less schematic view similar to that of Figure 5 but showing another embodiment of the present invention in which the flow regulator valve is provided in a single unit with the sight-feed at the instrument panel of the automobile.

Figure 7 represents a front elevational view of the unit containing the flow regulator valve and the sight-feed shown in Figure 6.

Figure 8 represents a vertical cross-sectional view along the line 8—8 of Figure 7.

Figure 9 represents a vertical cross-sectional view along the line 9—9 of Figure 7.

Figure 10 represents a vertical cross-sectional view of another embodiment of the present invention in which a timing wire is provided for regulating the time required for transfer of lubricant from the feeding chamber to the supply chamber, thereby to regulate the minimum period of time which must elapse after the motor is stopped and before it is restarted in order that an additional charge of lubricant be delivered to the motor upon such restarting.

Figure 11 represents a vertical cross-sectional view similar to that of Figure 10 but showing a somewhat different embodiment of the present invention in which a different means is provided to permit the insertion of the timing wire.

Figure 12 represents a vertical cross-sectional view of an integral unit which contains the feeding chamber and the supply chamber and which may be formed, for example, as a die-casting and which may be used in place of the individual feeding and supply chambers shown in Figures 1 to 4 inclusive; a different means for permitting the insertion of the timing wire being shown.

Figure 13 represents a horizontal plan view of the unit shown in Figure 12.

Figure 14 represents an enlarged fragmentary vertical cross-sectional view of the wall of the engine suction passageway showing one form of connection between the lubricator discharge conduit and the passageway.

Figure 15 represents a vertical cross-sectional view along the line 15—15 of Figure 14.

In one embodiment of the present invention, illustrated more particularly in Figures 1 to 4 inclusive, I may provide a container 20 which

serves as a lubricant reservoir and which has an upper threaded neck 21. The neck 21 is adapted to be screwed into a threaded socket 22 of a head 23.

Said head 23 may be provided with one or more openings 24 whereby the lubricator may be bolted or otherwise fastened to any convenient point of the automobile, preferably to the wall 25 which separates the engine compartment 26 from the operator's compartment 27, as shown in Figures 5 and 6.

A cylindrical feeding chamber 28 is supported within the uppermost part of said container 20 from said head 23 by means of a bolt 29 which passes through an opening 30 in said head 23 and which passes through a central opening 31 in the bottom wall 32 of the feeding chamber 28; a nut 33 being provided on the lowermost threaded portion 34 of said bolt 29 and being adapted to be tightened to hold said feeding chamber 28 firmly against a gasket 35 which is fitted within the socket 22.

An opening 36 is provided in the uppermost portion of said feeding chamber 28 to establish communication between said feeding chamber 28 and said container 20.

A cylindrical supply chamber 37 is suspended within said container 20 from said head 23 by means of a bolt 38 which passes through an opening 39 in said head 23 and which passes through a central opening 40 in the bottom wall 41 of said supply chamber 37; a nut 42 being provided upon the lowermost threaded portion 43 of said bolt 38 and being adapted to be tightened to hold said supply chamber 37 firmly against said gasket 35. Gaskets 91 and 92 are provided above the nuts 33 and 42 respectively to ensure a fluid-tight seal at the bottom of the feeding and supply chambers. Said supply chamber 37 has a greater axial dimension than that of the feeding chamber 28 and extends downwardly within said container 20 a predetermined distance below the bottom wall 32 of said feeding chamber 28.

An opening 44 is provided in the bottom wall 32 of the feeding chamber 28 and an opening 45 is provided in the bottom wall 41 of the supply chamber 37. A tube 46 connects the openings 44 and 45.

An apertured collar 47 is provided within said feeding chamber 28 directly above and surrounding said opening 44. A suitable filter 48 which may be a wire-mesh or felt screen or which may be of any other conventional construction is provided within said apertured collar 47. A tube 49 extends upwardly from the upper portion of said collar 47 and is open at its upper end 50 which is positioned at the uppermost portion of said feeding chamber 28.

A conduit 51 is connected to the intake manifold 52 or to some other convenient point in the suction passageway of the engine 53 and is connected at its other end to a threaded socket 54 in the head 23 by means of the threaded collar 55. A passageway 56 extends downwardly from the socket 54 and terminates in oppositely-extending horizontal passageways 57 and 58. Passageways 58 and 60 extend downwardly from the outermost ends of the passageways 57 and 58 respectively and communicate with the socket 22.

A J-shaped tube 61 has its longer arm 62 fitted within the passageway 59 and extends downwardly a relatively short distance within the

upper portion of said container 20 and has an opening 63 in the upper end of its shorter arm 64.

A tube 64 is fitted within the opening 60 and extends downwardly within said supply chamber 37 a predetermined distance below the bottom wall 32 of the feeding chamber 28 and has a restricted opening 65 in its lower end.

A socket 66 is provided within the upper portion of said head 23 and contains suitable filtering material 67. A vertical opening 68 extends downwardly within said head 23 from said socket 66 and communicates with the socket 22.

A J-shaped tube 69 has its longer arm 70 fitted within the vertical opening 68 and has a small aperture 71 in the upper end of its shorter arm 72 and extends to the bottom of the container 20.

A tube 73 is fitted about the upper end of the arm 72 in sealing relationship therewith and extended upwardly therefrom to a point adjacent to the gasket 35; the uppermost end of said tube being bent downwardly as at 74 and extending within the uppermost portion of said feeding chamber 28. A small opening 75 is provided in the lower end of the tube 73 at a point adjacent to the opening 71 in the arm 72 of the J-shaped tube 69 and below the normal level of lubricant within the container 20.

An internally-threaded socket 76 is provided upon the upper side of the head 23 and suitable filtering material 77 is disposed within the lowermost portion of said socket 76. A passageway 78 extends downwardly within said head 23 from said socket 76 and communicates with the supply chamber 37. A passageway 79 passes through the socket 76 and establishes communication between the atmosphere and said socket at a point just above the filtering material 77.

An externally-threaded flow regulator valve 80 is screw-threadedly disposed within said socket 76 and is adapted to close off the passageway 78 when said valve 80 is in its innermost position thereby to cut off communication between the supply chamber 37 and the atmosphere. When said valve 80 is unscrewed, the passageway 78 is uncovered and communication is re-established between said supply chamber 37 and the atmosphere.

A sight-feed indicator 81 may be provided within the conduit 51 to provide a means for checking on the performance of the lubricator. Said indicator 81 may contain a window 82 of glass, or crystal, plastic or the like through which the flow of lubricant from the lubricator to the intake manifold may be observed.

Said indicator may be placed just below or upon the dash-board 83 of the automobile, as shown in Figure 5, or at any other convenient point within the operator's compartment 27 or the engine compartment 26.

The operation of the embodiment shown in Figures 1 to 4 inclusive will now be described.

When the flow regulator valve 80 is in its open position so that the supply chamber 37 is in communication with the atmosphere through the passageway 78, the socket 76 and the passageway 79, the lubricator of the present invention will operate intermittently to supply a predetermined amount of lubricant to the valves and cylinders of the engine only when the engine is started "cold" and will, upon the continued operation of the engine, supply no additional lubricant. When the flow regulator valve 80 is in its open position, the lubricator of the present invention will not supply lubricant to the engine when the engine is started while still warm;

as for example, after the engine has been stopped and is then restarted after a period of 5 or 10 minutes. The lubricator will supply lubricant upon the start of the engine only after a predetermined time has elapsed since the last stopping of the engine; means being provided whereby the lubricator can be adjusted to vary the time which must elapse between the stopping and starting of the engine in order that the lubricator again supply lubricant.

In Figures 1 to 4 inclusive, the flow of lubricant is indicated by solid arrows while the flow of air is indicated by dotted arrows; alternate solid and dotted arrows indicating a mixture of lubricant and air.

When the motor is stopped and "cold," the lubricator of the present invention would appear as shown in Figure 1; the arrows being disregarded for the time being.

Thus, it can be seen, when the engine is stopped and "cold," a supply of lubricant 84 is present in the lower portion of the container 20 and additional lubricant is present in the lower portion of the supply chamber 37 and in the tube 46 connecting the supply chamber 37 with the feeding chamber 28. It will be noted that the relative sizes of the supply chamber and feeding chamber are so adjusted that, at this stage, the feeding chamber is empty and the surface of the lubricant in the supply chamber is at the same level as or at a slightly lower level than the bottom of the feeding chamber 28 and so that the tube 46 is just filled with lubricant. Before the engine is started, the submerged portions of the tubes 13 and 69 would also be filled with lubricant (as shown in Figure 3); Figure 1 showing their appearance after the engine has been started.

When the engine is started, the suction from the intake manifold 52 is transmitted to the conduit 51, through the sight-feed indicator 81, and to the socket 54, the passageway 56 and the passageways 57 and 58.

As illustrated in Figure 1, the suction thus created sucks in air from the interior of the container 20 through the opening 63 in the arm 64 of the J-shaped tube 61. At the same time lubricant is sucked upward from the supply chamber 37 through the opening 65 and the tube 164 due to the fact that atmospheric pressure is present upon the surface of the lubricant in the supply chamber 37.

The air from the J-shaped tube 61 and the lubricant from the tube 164 mix within the passageway 56 so that a mixture of air and lubricant passes through the conduit 51 to the intake manifold 52.

As sub-atmospheric pressure is created within the upper portion of the container 20, air is sucked in through the filtering material 67, the socket 66 and the J-shaped tube 69 until the level of liquid within the arm 70 of the tube 69 is depressed beyond the lowermost point 85 of the tube 69 whereupon the air rises upwardly within the arm 72, through the aperture 71 and upwardly within the tube 73, thus functioning as an air-lift which sucks in lubricant through the opening 75 and carries a mixture of air and lubricant upwardly within the tube 73 and out of the bent end 74 thereof and into the feeding chamber 28. Thus, after the pressure in the upper portion of the container 20 has been sufficiently lowered, the tubes 69 and 73 function as an air-lift to transfer lubricant from the container 20 to the feeding chamber 28.

Lubricant from the supply chamber 37 will continue to be sucked up through the tube 164 until its level drops below the opening 65 in said tube 164; air being simultaneously sucked in, through the opening 63, from the upper portion of the container 20.

As shown in Figure 2, after the level of the lubricant in the supply chamber 37 has dropped below the opening 65, the remaining lubricant in the supply chamber 37 will, upon continued operation of the engine, be forced upward through the tube 46 and the apertured collar 47 into the feeding chamber 28 (the chief function of the tube 49 being to permit escape of air to prevent disturbance in the flow in chamber 28) under the pressure of the atmosphere exerted through the open flow regulator valve 80; this being possible since the feeding chamber 28 is under sub-atmospheric pressure inasmuch as the suction from the opening 63 is transmitted to the feeding chamber through the opening 36 therein.

Thus, the amount of lubricant delivered to the intake manifold is predetermined and depends upon the lubricant contained within the supply chamber 37 between the original height A of lubricant and the height B of the opening 65; that is, the distance AB times the effective cross-sectional area of the supply chamber 37 (the volume of the bolt 38 and the volume of the walls of the tube 164 being deducted in calculating "effective cross-sectional area"). The remaining lubricant contained within the supply chamber 37 between the level B and its bottom C being transferred to the feeding chamber 28, as hereinabove described.

By regulating the length of the tube 164 and thus changing the level B of the opening 65 it is possible to vary the amount of lubricant delivered to the intake manifold.

Continued operation of the engine will suck in only air through the openings 63 and 65; it being applicant's belief that, under normal conditions of operation, it is unnecessary to provide lubricant in this fashion after an initial starting period has elapsed.

Continued operation of the engine will result in operation of the air-lift giving continuous transfer of lubricant from the container 20 to the feeding chamber 28. Excess lubricant will overflow from the feeding chamber 28 through the opening 36, and back into the container 20.

During such continued operation, air will be continuously sucked in through the open flow regulator valve 80 into the supply chamber 37 from which a portion of the air will pass upwardly through the tube 164 and into the conduit 51 while the remaining air passes through the tubes 46 and 49 into the upper portion of the feeding chamber 28, through the opening 36, into the container 20 and finally into the opening 63 in the J-shaped tube 61 and into the conduit 51. The air which is sucked in through the filtering material 67 and into the air-lift is delivered from the end 74 of the tube 73 into the upper part of the feeding chamber 28 from which it passes through the opening 36 into the container 20, through the opening 63 in the J-shaped tube 61 and into the conduit 51.

Thus, during such continued operation of the engine, the lubricator will be in the condition illustrated in Figure 2 in which the supply chamber contains no lubricant and the feeding chamber is filled with lubricant. The pressure within the supply chamber 37 is greater than the pres-

sure within the feeding chamber 28 due to the fact that more air is supplied to the supply chamber 37 (due to the greater capacity of the flow regulator valve 89) than is supplied to the upper portion of the feeding chamber 28. During this stage of operation, the lubricator will deliver only air to the intake manifold.

When the engine is stopped, the suction is no longer transmitted from the intake manifold to the conduit 51. Thereupon, the vacuum within the feeding and supply chambers and within the upper part of the container 20 is dissipated by air entering through the flow regulator valve 89 and through the filtering material 67 and the air-lift. The pressures within the feeding and supply chambers and within the upper portion of the container 20 are thereby equalized at atmospheric pressure and, as shown in Figure 3, the lubricant within the feeding chamber 28 drains down through the apertures in the collar 47 and the tube 46 and into the supply chamber 37 until the level of lubricant within the supply chamber 37 again reaches the height A, as shown in Figure 1.

The size of the apertures within the collar 47 can be adjusted to vary the time required for lubricant to drain from the feeding chamber 28 to the supply chamber 37. For example, the apertures in the collar 47 may be of such size that it would require 30 minutes for sufficient lubricant to drain into the supply chamber 37 to reach the level B and that it would require 60 minutes to reach the level A, shown in Figure 1.

Thus, if the engine were to be re-started, after having been stopped for less than 30 minutes, no lubricant would be sucked up into the conduit 51 and to the intake manifold upon such re-starting.

If, on the other hand, the engine were to be re-started, after having been stopped for more than 60 minutes, a full charge of lubricant would be delivered to the intake manifold upon such re-starting.

If the engine were to be re-started, after having been stopped for 45 minutes, approximately half of a full charge of lubricant would be delivered to the engine, since the level of the lubricant within the supply chamber 37 would be approximately half-way between the levels A and B, shown in Figure 1. The relationship between the time of flow and the rise in level within the supply chamber 37 is not a direct relationship since the rate of flow would be more rapid at the beginning than at the end of the draining period due to the fact that the difference in "head" is greater at the beginning than at the end.

However, the size of the aperture in the collar 47 and the size of the feeding and supply chambers can readily be calibrated to give accurate results.

By varying the height B of the opening 65 and by varying the size of the apertures in the collar 47, it is possible to provide any desired relationship between the stopping period and the amount of lubricant delivered upon re-starting.

As shown in Figures 10 and 11, it is possible to change the construction illustrated in Figures 1 to 3 in order to permit the operator readily to vary the lubricant so delivered upon re-starting without changing either the collar 47 or the tube 164.

In Figure 10 the tube 46-a is made flexible and is fitted about downwardly-extending necks 86 and 87 formed at the openings 44 and 45 respectively.

By unscrewing the container 20 from the head

23, the operator can remove the tube 46-a from the neck 86 and can then insert a timing wire 88 so that said timing wire partially obstructs the flow of lubricant through the neck 86 and into the tube 46-a. In this way, the time required for the transfer of lubricant from the feeding chamber 28 to the supply chamber 37 is increased. By providing a plurality of suitably calibrated interchangeable timing wires having different diameters, it is possible to regulate the time for such transfer, as desired.

The embodiment shown in Figure 11 does not include a flexible tube but, instead, includes the tube 49 which is generally J-shaped and also includes a threaded opening 89 in the head 23 directly above the upper open end 50 of the tube 49. The opening 89 is normally closed by the screw plug 90. The plug 90 can be unscrewed to permit the insertion of the timing wire 88 from above the head and through the tube 49 to partially obstruct the flow of lubricant through the tube 46; the lowermost end of the timing wire resting upon the bend of the tube 49. It is thereby possible to insert and remove and to interchange timing wires merely by unscrewing the plug 90 and without having to unscrew the container 20 from the head 23.

I will now describe the functioning of the embodiment shown in Figures 1 to 4 inclusive when the flow regulator valve 89 is closed to give a continuous flow of lubricant to the intake manifold as long as the engine is operating.

When the flow regulator valve 89 is closed the lubricator, before the starting of the engine, is in generally the same condition as shown in Figure 1.

When the engine is started, the suction is transmitted from the intake manifold to the conduit 51 and to the J-shaped tube 61 and the tube 164.

As described hereinabove, in connection with Figures 1 and 2, the suction thus transmitted will suck air from the upper portion of the container 20 through the opening 63 in the J-shaped tube 61 and will suck up lubricant from the supply chamber 37 through the opening 65 of the tube 164; the air-lubricant mixture which is formed in the passageway 58 being carried through the conduit 51 to the intake manifold.

As described hereinabove, the sub-atmospheric pressure produced within the container 20 will cause air to enter through the filtering material 67 and to operate the air-lift to transfer lubricant from the container 20 to the feeding chamber 28.

Upon operation of the engine, the level of lubricant within the supply chamber 37 will drop to the point B and will remain at that point as shown in Figure 4.

A lubricant-air mixture will be sucked continuously from the feeding chamber 28 through the tube 46 into the supply chamber 37 to maintain the level of lubricant within the supply chamber 37 at the point B.

In this way, when the flow regulator valve 89 is closed, a continuous supply of lubricant-air mixture is delivered to the intake manifold 52 as long as the engine is operating; the lubricant-air mixture being continuously transferred from the container 20, through the feeding chamber 28, the tube 46, the supply chamber 37, and the conduit 51 to the intake manifold 52.

After the engine has been stopped, the lubricator remains in the same condition, shown in Figure 4, since air entering through the filtering

material 67 into the upper portion of the container 20 is distributed through the opening 36 to the feeding chamber 28 and through the opening 63, the J-shaped tube 61, the passageways 51 and 58, the tube 164 and the opening 65 to the supply chamber 37 so that the container 20, the feeding chamber 28 and the supply chamber 37 all reach atmospheric pressure.

It can be seen that the operator of the automobile may readily shift from intermittent to continuous lubrication or vice versa, as desired, merely by closing or opening the flow regulator valve 80. This is particularly desirable since, under special and unusual operating conditions, it may be preferable to provide a continuous flow of lubricant whereas, normally, initial lubrication would be sufficient.

The lubricator of the present invention has the decided advantage of enabling the driver to use a continuous flow for a certain period of time in order thoroughly to flush or purge the motor. Thereafter, the use of intermittent flow will keep the motor at the high stage of efficiency produced by the previous continuous treatment. Formerly, this could be accomplished only by way of a time-consuming and expensive operation of removing the spark plugs or the air-cleaner of the engine.

The lubricator is adapted to be connected, by means of the conduit 51, with the engine 53 at any suitable point in the intake manifold 52 thereof at or beyond the carburetor, so that during engine operation the manifold suction or depression is communicated to the lubricator. The conduit 51 may be connected into the engine suction passage in any suitable manner, although the particular form of attachment shown in Figures 14 and 15 has been found to be especially advantageous because of its simplicity and adaptability to practically all installations. The particular advantage of this type of connection is that it permits attachment of the conduit 51 at any gasketed joint between the intake manifold 52 and the engine or carburetor, without requiring any special parts or fittings, or in fact any extra parts whatsoever.

As shown in Figures 14 and 15, simply by flattening the end portion of the conduit 51 as at 93 and inserting the flattened end 93 between the usual gaskets 94 and 95 and within transverse registering grooves 96 and 97 formed in the gaskets 94 and 95 respectively, a fluid-tight joint is formed about the flattened end 93 of the conduit 51 when the parts 98 and 99 are bolted together to compress the gaskets. These parts 98 and 99 may, for example, be sections of the intake manifold 52 or the joint parts at the connection between the manifold and carburetor. By outwardly flaring the innermost end of the conduit 51, as indicated at 100, the pipe is effectively prevented from being pulled out of the joint.

Instead of providing the flow regulator valve directly upon the head 23, it is possible to position the valve upon a common unit with the sight-feed indicator so that the valve is more readily accessible to the operator as shown in Figures 6, 7, 8 and 9.

In this embodiment, the sight-feed and flow regulator unit 101 may be clamped to the lowermost edge of the instrument panel or dash-board 83 by means of the bolt 111.

A socket 76—a is provided upon the head 23—a and is similar to the socket 76 shown in Figures 1 to 4 inclusive except that the horizontal passageway 79 is omitted.

A tube 102 is connected to the socket 76—a by means of the threaded collar 103. The other end of the tube 102 is connected, by means of the threaded collar 104, to a passageway 105 in the unit 101 leading to a threaded opening 106.

Another passageway 107 extends upwardly from the opening 106 to a socket 108 in which is contained a screen 109 and a strip of felt 110 or other suitable filtering material for cleaning the air to be sucked into the lubricator.

A flow regulator valve 80—a is screw-threadedly engaged within the threaded opening 106 and is adapted to seal the passageway 105 when the valve is screwed into its innermost position. Thus, the flow regulator valve 80—a functions in exactly the same way as the valve 80; the supply chamber 37 being open to the atmosphere when the valve 80—a is open and being closed off when the valve 80—a is shut.

The unit 101 also contains the window 82 which may be of glass or crystal or plastic as described hereinabove to indicate, to the operator, whether or not lubricant is flowing from the lubricator, through the conduit 51, to the intake manifold 52. As shown particularly in Figure 9, suitable connections are provided for the conduit 51—a leading to the lubricator and the conduit 51—b leading to the intake manifold 52.

While, in Figures 5 and 6, the lubricator is shown as being attached to the engine-side of the wall 25 separating the engine compartment 26 from the operator's compartment 27, it is possible to place the lubricator at any other convenient point, as for example, upon the operator's side of the wall 25. This latter position, in fact, may sometimes be preferred where the lubricator shown in Figures 1 to 4 inclusive is employed since the flow regulator valve 80 is then positioned adjacent to the operator and may be adjusted by him without having to get out of the car and to raise the hood, as will be necessary in the arrangement shown in Figure 5.

While, in Figures 1 to 4, inclusive, the feeding chamber 28 and the supply chamber 37 are shown as two separate and distinct cylindrical members connected by the tube 46, it is possible to form the feeding and supply chambers as a single integral unit, as for example, by die-casting.

Thus, in Figure 12, a unit 112, which may be die-cast, includes the generally cylindrical supply chamber 113 having the bottom wall 114 in which is the central opening 115 whereby the unit 112 may be supported from the head by a bolt and nut (not shown).

A generally annular feeding chamber 116 is provided about the upper portion of the cylindrical supply chamber 113 and communicates therewith by means of a vertical passageway 117 and a horizontal passageway 118.

The outermost end of the horizontal passageway 118 is threaded and is adapted to receive the threaded bolt 119 which may be removed to permit the insertion of a timing wire 88—a for regulating the time required to transfer lubricant from the feeding chamber 116 to the supply chamber 113.

It is possible to dispense with the flow regulator valve 80 in the embodiment shown in Figures 1 to 4 inclusive and to have the opening leading to the supply chamber blocked and closed off to provide continuous injection of lubricant where operating conditions are such as to make this desirable. It is also possible to place either the sight-feed indicator 81 or the unit 101 at a point other than the dash-board or instrument

panel; as for example, inside of the engine compartment 26.

It is also possible to dispense entirely with the sight-feed indicator.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

The invention having been hereinabove described, what is hereby claimed as new and desired to be protected by Letters Patent, is:

1. An engine lubricator including a lubricant reservoir, a lubricant feed chamber disposed within the upper part of said reservoir and vented thereto, means for transferring lubricant from said reservoir to said feed chamber during operation of the engine, a closed supply chamber disposed within said reservoir and extending downward therein beyond said feed chamber, a passageway connecting lower portions of said feed chamber and said supply chamber and permitting flow of lubricant therebetween, a branched suction conduit operatively connected to the engine and separately communicating with the upper portion of said reservoir and with an intermediate portion of said supply chamber, said conduit being adapted simultaneously to suck fluid from said upper portion of said reservoir and from said intermediate portion of said supply chamber, and a manually-operable air valve connected to said supply chamber and opening to the exterior of said lubricator, said valve being adapted to be closed whereby said feed chamber and said supply chamber are kept at generally the same reduced pressure during operation of the engine to permit continuous drainage of lubricant from the feed chamber to the supply chamber and continuous transfer of lubricant from said intermediate portion of said supply chamber through said conduit to the engine, said valve being adapted to be opened to admit air to said supply chamber whereby said supply chamber is kept at an appreciably higher pressure than said feed chamber during operation of the engine to prevent drainage of lubricant from the feed chamber to the supply chamber during operation of the engine and thereby to interrupt transfer of lubricant to the engine after an initial period of engine operation and after the level of lubricant in said supply chamber has dropped below said intermediate portion thereof, and to permit equalization of pressure and drainage of lubricant from said feed chamber to said supply chamber after termination of engine operation thereby gradually to accumulate an initial charge of lubricant in said supply chamber.

2. An engine lubricator including a lubricant reservoir, a lubricant feed chamber disposed within the upper part of said reservoir and vented thereto, an air-lift disposed within said reservoir and adapted to transfer lubricant from said reservoir to said feed chamber during operation of the engine, a closed supply chamber disposed within said reservoir and extending downward therein beyond said feed chamber, a passageway connecting lower portions of said feed chamber and said supply chamber and permitting flow of lubricant therebetween, a branched suction conduit operatively connected to the engine and communicating with the upper

portion of said reservoir and with an intermediate portion of said supply chamber, and a manually-operable air valve connected to said supply chamber.

3. An engine lubricator including a lubricant reservoir, a lubrication feed chamber disposed within the upper part of said reservoir and vented thereto, an air-lift disposed within said reservoir and adapted to transfer lubricant from said reservoir to said feed chamber during operation of the engine, a closed supply chamber disposed within said reservoir and extending downward therein beyond said feed chamber, a passageway connecting lower portions of said feed chamber and said supply chamber and permitting flow of lubricant therebetween, a removable constricting means disposed within said passageway and adapted to reduce the rate-of-flow of lubricant therethrough, a branched suction conduit operatively connected to the engine and communicating with the upper portion of said reservoir and with an intermediate portion of said supply chamber, and a manually-operable air valve connected to said supply chamber.
4. An engine lubricator comprising a head, a lubricant reservoir removably suspended from said head, a lubricant feed chamber suspended from said head and disposed within the upper part of said reservoir and vented thereto, an air-lift disposed within said reservoir and adapted to transfer lubricant from said reservoir to said feed chamber during operation of the engine, a closed supply chamber suspended from said head and extending within said reservoir downward beyond said feed chamber, a passageway connecting the lower portions of said feed chamber and said supply chamber and permitting flow of lubricant therebetween, a branched suction conduit operatively connected to the engine and separately communicating with the upper portion of said reservoir and with an intermediate portion of said supply chamber, said conduit being adapted simultaneously to suck fluid from said upper portion of said reservoir and from said intermediate portion of said supply chamber, and a manually operable air valve connected to said supply chamber and opening to the exterior of said lubricator, said valve being adapted to be closed whereby said feed chamber and said supply chamber are kept at generally the same reduced pressure during operation of the engine, said valve being adapted to be opened to admit air to said supply chamber and thereby to keep said supply chamber at an appreciably higher pressure than said feed chamber during operation of the engine.
5. An engine lubricator including a lubricant reservoir, a lubricant feed chamber disposed within the upper part of said reservoir and vented thereto, means for transferring lubricant from said reservoir to said feed chamber during operation of the engine, a closed supply chamber disposed within said reservoir and extending downward therein beyond said feed chamber, a passageway connecting lower portions of said feed chamber and said supply chamber and permitting flow of lubricant therebetween, a branched suction conduit operatively connected to the engine and separately communicating with the upper portion of said reservoir and with an intermediate portion of said supply chamber, said conduit being adapted simultaneously to suck fluid from said upper portion of said reservoir and from said intermediate portion of said supply chamber, and a manually-operable air valve con-

nected to said supply chamber and opening to the exterior of said lubricator, said valve being adapted to be closed whereby said feed chamber and said supply chamber are kept at generally the same reduced pressure during operation of the engine to permit continuous drainage of lubricant from the feed chamber to the supply chamber and continuous transfer of lubricant from said intermediate portion of said supply chamber through said conduit to the engine, said valve being adapted to be opened to admit air to said supply chamber whereby said supply chamber is kept at an appreciably higher pressure than said feed chamber during operation of the engine to prevent drainage of lubricant from the feed chamber to the supply chamber during operation of the engine and thereby to interrupt transfer of lubricant to the engine after an initial period of engine operation and after the level of lubricant in said supply chamber has dropped below said intermediate portion thereof, and to permit equalization of pressure

5 and drainage of lubricant from said feed chamber to said supply chamber after termination of engine operation thereby gradually to accumulate an initial charge of lubricant in said supply chamber, the respective sizes of said feed chamber and supply chamber and the rate of drainage from the former to the latter being predetermined to provide a full initial charge of lubricant upon restarting of engine operation only 10 after the engine has been stopped sufficiently long to permit complete drainage of said feed chamber and to provide no initial charge of lubricant upon restarting of engine operation when the engine has been stopped insufficiently long 15 to permit the level of drained lubricant in the supply chamber to reach the intake end of the suction conduit therein and to provide a less-than-full initial charge of lubricant upon restarting of engine operation when the engine has been stopped for a period intermediate the first-mentioned and second-mentioned periods of time. 20
